UNITED STATES PATENT OFFICE.

HARRY S. FREEMAN, OF DETROIT, AND FREDRICK ZENKER, OF HIGHLAND PARK, MICHIGAN, ASSIGNEES TO SQUARED COMPANY, OF DETROIT, MICHIGAN, A CORPORATION OF MICHIGAN.

ELECTRIC SWITCH.

1,315,593.

Specification of Letters Patent.

Patented Sept. 9, 1919.

Application filed October 29, 1917. Serial No. 198,919.

To all whom it may concern:

Be it known that we, HARRY S. FREEMAN, a citizen of the United States, residing at Detroit, in the county of Wayne and State of Michigan, and FREDRICK ZENKER, a subject of the Emperor of Germany, residing at Highland Park, county of Wayne, and State of Michigan, have invented certain new and useful Improvements in Electric Switches, of which the following is a specification.

The invention relates to electric switches of the fuse holding type and with respect to certain features thereof it is an improvement upon the switch shown and described in our co-pending application Serial Number 198,382, filed October 25, 1917.

The present invention has for one of its principal objects to provide an organization of contacts and conductors so constructed and arranged that a minimum amount of space is required and the leverage is considerably increased.

Another object of the invention is to provide a simple, durable and inexpensive fuse holder and combined circuit operating device wherein the fuse holding contacts are spaced away from and independent of the pivotal means and wherein the ease of operation of attaching and detaching the fuse is increased.

Other objects will be in part obvious and in part pointed out hereinafter.

The invention accordingly consists of the various features of construction, combination of elements and arrangements of parts which will be exemplified by the construction hereinafter set forth and the scope of the invention of which will be indicated in the following claims.

40 In the accompanying drawing wherein is shown one of various possible embodiments of the invention—

Figure 1 is a view in side elevation of a switch comprising features of the invention.

45 Fig. 2 is a sectional view taken on the line 2—2 of Fig. 1.

Fig. 3 is a sectional view taken on the line 3—3 of Fig. 1; and

50 Fig. 4 is a sectional view taken on the line 4—4 of Fig. 3.

Referring now more particularly to the drawing, there is indicated at 1 a base of insulating material upon which are mounted clip contacts 2 and 3. Each of these contacts is connected with a terminal 4 by means

of a connecting strip 5 of electrical conductivity. The contact 2 is formed with a flat attaching portion 7 and upstanding side walls 8, the latter being bowed inwardly as at 9 and extended upwardly again in the form of spaced parallel walls or jaws 10.

A carrier or bridging element 11 of insulating material has attached thereto an angle member 12 of relatively thin flat metal stock, one side or blade 13 of the angle member 65 providing a means of attachment to the carrier 11 and the other side or blade 14 extending downwardly between the walls or jaws 10 of the contact 2. Both the blade 14 and the walls 10 are apertured to receive the shank 15 of a pivot bolt 16, and the walls 10 are suitably compressed against the blade 14 by spring washers 17 bearing against the outer surfaces of the walls 10 and reacting against the head 18 of the pivot bolt and the 75 adjustable nut 19 thereof, respectively.

From the foregoing it will be obvious that by movement of the handle 20 the carrier 11 may be moved relatively to the base 1 about the pivot bolt 16. One of the purposes of 80 this movement is to provide for relative engagement and disengagement between the contact 3 on the base and a blade contact 25 formed on a metal conductor strip 26 which in turn is secured to the carrier 11 by means 85 of a screw 27. From Fig. 3 of the drawing it will be apparent that this blade 25 is offset laterally from the carrier 11 and longitudinally positioned about midway of the carrier. Near the free end of the carrier 90 where the screw 27 provides the point of attachment for the conductor 26 thereto, there is provided a clip contact 30 in electrical communication with said conductor.

This contact is shaped with a flat attaching portion 31, side walls 32, bowed inwardly as at 33 and continued in the form of spaced parallel compression jaws 34, the latter being adapted to receive one of the flat terminals 35 of an inclosed fuse 36, the other 105 flat terminal 37 of which engages with similar compression jaws 38 on a contact clip 40 connected to the angle member 12 and similar in shape and construction to the contact clip 30. For convenience the clips 30 and 105 40 may be termed "fuse holding clips."

The contact 3 comprises a flat attaching portion 42, upstanding side walls 43, bowed inwardly and downwardly as at 44 and forming contact jaws 45 adapted to receive 110

the blade 25 and exert a suitable electrical contacting and retaining pressure thereon.

With the parts in the positions shown in Fig. 1 of the drawing, an electrical circuit 5 is established from terminal 4, through connector 5, contact 2, angle member 12, contact 40, fuse terminal 37, through the fuse, through fuse terminal 35, contact 30, conductor 26, blade contact 25, contact 3, opposite 10 site end connector 5 to opposite end terminal 4.

The leverage is increased by offsetting the blade 25 and bringing it longitudinally nearer the pivot point than the contact 30.

15 Furthermore, the fuse and fuse holding contacts are spaced away from the pivot and the circuit controlling contacts 25 and 3, making for greater accessibility and longitudinal compactness.

20 As many changes could be made in the above construction and as many apparently widely different embodiments of the invention could be made without departing from the scope thereof, it is intended that all 25 matter set forth in the foregoing description or shown in the accompanying drawings shall be interpreted as illustrative and not in a limiting sense.

What is claimed is:

30 1. In a fuse-holding switch, in combination, a base, a pair of spaced apart contacts mounted thereon, a bridging element pivotally mounted for movement relatively to said base, a second pair of contacts 35 mounted on said bridging element and adapted for coöperative association with said base contacts, and a pair of fuse receiving and holding contacts respectively connected to said second pair of contacts; 40 one of said second pair being offset longitudinally of and transversely of its fuse receiving contact.

2. In a fuse-holding switch, in combination, a base, a pair of spaced apart contacts 45 mounted thereon, a bridging element pivotally mounted for movement relatively to said base, a second pair of contacts mounted on said bridging element and adapted for coöperative association with said base contacts, a pair of fuse receiving and holding contacts respectively connected to said second pair of contacts; one of said second pair being offset longitudinally of and transversely of its fuse receiving contact, and the 55 other contact of said second pair being pivotally connected to one of the base contacts.

3. In a fuse-holding switch, in combination, a base, a pair of spaced apart contacts mounted thereon, a bridging element pivotally mounted for movement relatively to 60 said base, a second pair of contacts mounted

on said bridging element and adapted for coöperative association with said base contacts, a pair of fuse receiving and holding contacts respectively connected to said second pair of contacts; one of said second pair being offset longitudinally of and transversely of its fuse receiving contact, and an inclosed fuse having terminals adapted to engage with the fuse receiving contacts. 70

4. In a fuse-holding switch, in combination, a base, a pair of spaced apart contacts mounted thereon, a bridging element pivotally mounted for movement relatively to said base, a second pair of contacts 75 mounted on said bridging element and adapted for coöperative association with said base contacts, a pair of fuse receiving and holding contacts respectively connected to said second pair of contacts; one of said second pair being offset longitudinally of and transversely of its fuse receiving contact, the other contact of said second pair being pivotally connected to one of the base contacts, and an inclosed fuse having terminals adapted to engage with the fuse receiving contacts. 80

5. In a fuse-holding switch, a base, a pair of contacts mounted thereon and spaced apart substantially less than the length of a fuse, a bridging element movable relatively to said base, a second pair of contacts mounted thereon and spaced apart to engage with said first pair, a third pair of contacts carried by said bridging element, 95 one of which electrically connects with one of the second pair of contacts and the other of which electrically connects with the other of said second pair, said third pair constituting fuse connecting contacts and being 100 spaced apart to receive a fuse longitudinally between them.

6. In a fuse-holding switch strip, a base, a pair of contacts mounted thereon and spaced apart substantially less than the length of a fuse, a bridging element movable relatively to said base, a second pair of contacts mounted thereon and spaced apart to engage with said first pair, a third pair of contacts carried by said bridging element, one of which electrically connects with one of the second pair of contacts and the other of which electrically connects with the other of said second pair, said third pair constituting fuse connecting contacts and being spaced 110 apart to receive a fuse longitudinally between them, and an inclosed fuse having extending knife blade terminals adapted to be connected to said fuse connecting contacts. 115
